UNITED STATES PATENT OFFICE.

JAMES G. SHECKELS, OF CINCINNATI, OHIO, ASSIGNOR OF ONE-HALF TO EDWARD ALBIEZ, OF CINCINNATI, OHIO.

REFRIGERATOR CONSTRUCTION.

Application filed September 10, 1924. Serial No. 736,918.

To all whom it may concern:

Be it known that I, JAMES G. SHECKELS, a citizen of the United States, residing at Cincinnati, in the county of Hamilton and State of Ohio, have invented new and useful Improvements in Refrigerator Constructions, of which the following is a specification.

This invention relates to an improved refrigerator construction and particularly to 10 that portion of a refrigerator which supports the refrigerating elements.

An object of my invention is to produce an improved refrigerator construction which is particularly designed to bring about conditions of increased refrigeration with greater efficiency than has been attained by other constructions known to me.

A further object is to produce a refrigerator construction which is readily adaptable 20 and as efficient in its operation for use with cakes or crushed ice as it is for use with the usual refrigerating coils of refrigerating apparatus.

A further object of my invention is to produce 25 a refrigerator construction which may be readily dismantled or taken apart for the purposes of cleaning or repairing or replacing the parts thereof, so that perfect preservation of the refrigerator and its contents is assured throughout.

These and other objects are attained in the construction described in the following specification and illustrated in the accompanying drawings, in which:

Fig. 1 is a fragmental perspective view of 35 the portion of a refrigerating mechanism which embodies my invention, certain parts having been shown removed and broken away for clearness of illustration.

Fig. 2 is a transverse sectional view taken 40 on the line 2—2 of Fig. 1, all parts being shown in position.

Fig. 3 is an enlarged perspective view of 45 a detail of my invention, portions being shown broken away for construction illustration.

Fig. 4 is a fragmental perspective view of a detail of my invention.

Fig. 5 is a view similar to Fig. 2, but of 50 the novel features slightly modified and taken on the line 5—5 of Fig. 6.

Fig. 6 is an enlarged fragmental perspec-

tive view of the modified form of construction shown in Fig. 5, certain parts having been shown removed and broken away for 55 clearness of illustration.

Fig. 7 is a view similar to Fig. 5 but showing the use to which the modified form is placed.

Although my improved refrigerator is as 60 readily adaptable to use with refrigerating coils as with ice, I have chosen to describe the form using the coils, as the preferred form of my invention. The structure which embodies the features of novelty is located between the side walls 8 and 9 of the usual refrigerator casing and at a sufficiently spaced distance below the top 10 of the casing. Extending from side to side of the casing are a series of uniformly spaced beams 70 11. Upon these beams and extending from front to rear of the casing are deflecting walls 12 and 13. Beneath these walls and extending toward each other are baffle platforms 14 which are located removably between adjacent beams. Each of these platforms is inclined downwardly toward the center in order to have its inner edge immediately over a gutter. The inner edges of the platforms are spaced apart to form a central 80 space 15 and on each side of the passages are gutters 16 and 17 which have been provided to catch the drippings from the platforms. Upon the beams and either integral therewith or added thereto as shown in Figs. 1 85 and 6, have been located supports 18 and 19 which extend above the deflecting walls. These supports are adapted to support refrigeration pipes 20. Each of the elements I have described, as for example, the gutters 16 and 17, the supports 18 and 19, the platforms 14 and the walls 8 and 9 are suitably insulated as by materials 21 and then covered with metal 22, the material 21 serving to prevent the water of condensation 90 from the metal 22, from coming into contact with and thereby causing deterioration of the wood.

The operation of the construction when refrigeration is brought about is to cool the air and cause it to descend over the downwardly inclined platform surfaces toward the central space 15. The cool air will drop as indicated by the central arrows, and

- gradually becoming warmed, will arise along the walls 8 and 9, between the walls 8, 12 and 9, 13 and will become cooled as it again becomes chilled by contact with pipes 20.
- 5 In arising some of the warm air will engage the under inclined surface of the platforms and will be directed, with the remainder of the air, between the walls 8, 12 and 9, 13 and thence be in a position to 10 again be cooled and directed downwardly through the center opening.

In the construction shown in Figs. 5, 6 and 7 there is provided an additional element 23 which is in the nature of a water shed located over the opening 15. This water shed is supported on the beams 11, and has its outer edges sloping toward the platforms 14 but spaced from them so that moisture dripping therefrom will fall upon 20 the platforms and be diverted therefrom into the gutters 16 and 17. Also space between the water shed and platforms allows the air to pass downwardly as in the previous construction. Upon the platforms and 25 water shed of this modified construction the cakes of ice 24, which are used instead of the refrigerating coils 20, may be placed, if crushed ice is used suitable platforms may be provided to hold same from clogging the 30 air spaces. Each gutter is provided with

a downspout 25 which drains the water from it to the sewer.

Having thus described my invention what I claim is:—

A refrigerator construction comprising a 35 casing, a series of beams below the top of the casing, extending in spaced relation from front to back, the ends of the beams being supported by the sides of the casing, a series of independent removable baffle platforms 40 supported by and between the beams and inclining downwardly from the sides of the casing toward the center and spaced apart so as to leave a central air passage, gutters beneath the lower edges of the baffle platforms, supports located in spaced relation on each of the beams and projecting above the baffle platforms on a horizontal line with the top plane of the water shed, a removable water shed supported by the beams in the 50 spaces between the supports and located between the opposite sets of baffle platforms to act as a bridge over the central air passage, adapted to drain unto the platforms and spaced therefrom, said water-shed, supports, and baffle platforms being adapted to receive refrigerating elements thereon.

In witness whereof, I affix my signature.

JAMES G. SHECKELS.
